UNITED STATES PATENT OFFICE.

PEARL DOLES BELL, OF NEW YORK, N. Y.

COIN-CONTROLLED DOCUMENT DEVICE.

Application filed July 13, 1927. Serial No. 205,327.

This invention has reference to coin-controlled devices, in which a document will be impressed or printed by various data, and which is actuated only after insertion of 5 the proper coin.

One object of the invention is to provide such a device that will cause the printing of the exact time on the document, and which will further present the document at a 10 window to receive writing such as an autograph.

A further object is to provide means for making a record of the document as printed in the casing and which record is retained 15 in the casing when the document is delivered; and which device can produce a series of such documents in succession, and a record of each document will be retained in the casing.

20 Another object of the invention is to provide means for causing the same operation of the printing means to show the date and time, and also the autograph, by the insertion of coins of different sizes; but which 25 latter operation will cause a special impression on the document to indicate the coin by which it was operated.

In the accompanying drawings showing one embodiment of my invention.

30 Figure 1 is a perspective view.
Fig. 2 shows the document slip.

Fig. 3 shows a printing means for the name.

Fig. 4 is a side elevation with the side 35 plate removed.

Fig. 5 is a rear view of part of the printing mechanism.

Fig. 6 shows the frame.
Fig. 7 is a detail of the coin mechanism.

40 Fig. 8 shows part of the coin release.

Fig. 9 shows the printing mechanism.

As shown in the drawings the casing comprises a back plate 3 with side plates 4 and 5, having extensions 6 and 7 at the 45 lower part to receive a bridge plate 8 supported thereon, with other cross plates 9 and 10 supported by the side plates. This plate 9 receives a web 11 from a roll 12, which web passes under a guide 13, then 50 over the plate 8, and down to engage a winding roll 14. A cross shaft 15 carries tooth disks 16, that project through slots 17

in the plate 9 to engage the web having suitable holes as shown in Fig. 2. A belt 18 drives the roll 14 from the shaft 15, 55 which belt is under tension and may be a coil of wire.

Another web 19 is carried by a roller 20 at the top, and passes down around a guide roll 21 and then moves forward on top of 60 the web 11, see Fig. 4, and is pressed against the tooth wheel or disk 16 by roll 22, so that it will be advanced with the web 11 over the plate 9. The web 11 is intended to receive a carbon copy of the record on the 65 web 19, and a band 23 of carbon paper passes around four rolls 24, 25, 26 and 27 and is endless, and will be advanced between the two webs. As these webs are advanced by the two disks, the upper web 19 70 will pass forward under the plate 28 and out through a slot 29 at the front. Means to be set forth, cut portions of this web as advanced, while the other web 11 will be wound up on the roll 14. 75

Means are provided in the machine for printing the exact hour and the date on the two webs on the plate 9. This mechanism can be of the conventional form well known as a time stamp and will include suitable 80 printing wheels denoted generally by 29', connected with a clock 30 for proper control. These wheels are carried by a frame denoted generally by 31, suspended on each side by links 32, 33 from the side plates, 85 normally held raised by springs 34, and which frame is depressed to cause the type on the wheels to print on the webs held by the plate 9.

The coin controlled mechanism is shown to receive three different size coins, such as a nickel, a dime and a quarter. A box 35 is shown having slots 36, 37 and 38 of different lengths for these coins. When a coin is inserted in slot 36 and pushed down it 95 will engage a lever 39 and swing this lever back as shown in Fig. 7, which by a link 40 will swing a rack bar 41 to the rear and hold it in this position. The coin is now supported by the lever 39 and an arm 110 100 and an arm 42 on a shaft 43 which is rocked at a later stage will release the coin.

Two similar rack bars 44 and 45 are operated by links 46 and 47, from levers 48 and

49 similar to lever 39, see Fig. 6. These three levers are arranged to be actuated by the three different coins, and arms similar to 42 on shaft 43 cause the release of any coin 5 in these three locations. The lower ends of these rack bars are slotted and are guided by the shaft 52 of the printing mechanism.

A main operating lever 53 is mounted on a cross shaft 54 that projects through a side 10 plate. This shaft carries a pinion 55 of sufficient length to be engaged by either of the racks 41, 44 or 45, when swung back on insertion of a coin. Thereupon the swinging forward and down of this lever will 15 through this pinion move the engaged rack downwardly. Each of these racks has a type on the lower end arranged to engage the two webs and make an impression, that will indicate the coin by which the operation 20 is produced. This downward movement of any rack bar will carry down an arm thereon 56, 57 or 58 for the three rack bars; and such arm will engage a rod 59 carried by the frame 31 that supports the 25 type wheels as described. Thereby the swinging down of the handle will bring the type wheels to make an impression on the webs, at the same time that the selector rack bar moves down to make its impression. It 30 will be understood that only the selected bar will operate, and the other two bars will be locked normally by cross pins 60 thereon that engage a stop plate 61, see Fig. 7.

This swinging down of the links 32 and 33 35 will serve to actuate the web disks, by a lever 62 on the link, that engages pins 63 on a gear 64, by a hook end 65. An arm 66 on lever 62 has a hook end 67 that engages these pins on opposite sides of the gear center, and the arm 66 is pressed toward the arm 62 by a spring 68, so that the hooks work alternately when moved up and down. The gear 64 engages a gear 70 fast on shaft 15, by this means when the frame and links 45 move down the web will be advanced a certain distance by the hook 65, and when the link moves up the other hook 67 will again advance the web so that the portion that receives the impression will be moved along 50 near the window in front plate 28, where the user can write the name or other desired matter. In Fig. 3 a special wheel 71 is shown that turns on an arm 72 carried by a rock bar 73. This can be swung over the 55 window 2 and the characters on the wheel when turned will print as desired.

Means are provided for locking the control lever 53 when swung down, and an arm 74 at the front carries a latch 75 that will 60 engage a pin 76 on the arm 77 fast to shaft 54. When the lever 53 is swung down to print and released, it will be readily understood that the tooth on latch 75 will ride free over pin 76 on arm 77 and permit a very small return movement of the printing

wheels by spring 34, before the pin 76 is held by the latch so that the type are clear of the web as advanced.

At this stage the user writes the autograph on the upper web, and the carbon copy is 70 made on the lower web. Then the arm 74 is swung to release the lever and carriage, and the spring 34 will return these parts to upper position. The lever 62 will further advance the tooth disk by the hook arm, and the webs 75 will be advanced, the upper web passing forward through the slot 29. At the latter portion of this operation, a cutter blade 177 will be operated by an arm 78 and link 79, from an arm 80 fast to the link 33, that will sever 80 the upper web, but not the lower one that passes below the roller 13.

To release the coin, a link 81 is connected with the arm 74 and to an arm 82 on the shaft 43, so that this lever will serve to release the coin in any of the slots and thus restore these parts. The three arms 42 when swung will serve to move the coin sidewise, see Fig. 8, by having an inclined or cam edge 85 that will engage the coin as held between 90 levers 39 and 110, and will shift it sidewise to be free to drop down, as shown in Fig. 8.

Opposite the coin arms 39, 48 and 49, are three arms 110, that are spring-pressed toward the said levers, against pin stops 113. 95 When the coin is first inserted, it will force back these three levers 110, until it passes through the upper slot, when such levers by their strong springs will actuate the said levers 39, 48 and 49 with their connected 100 links and rack bars.

Means are further provided for a shutter to normally close the window 2, and as shown a plate 90 is carried by the lever or arm 80 fast to the link 33. This shutter will 105 normally close the window and prevent access to the web below the window. When the operation of the mechanism as set forth takes place and the link 33 swings down, the shutter will be withdrawn by the arm 80 and 110 expose the web.

It should have been stated that as soon as either of the rack bars moves down the pins 60 thereon will be held by plate 91 in engagement with the pinion 54 and will 115 engage this pinion until the racks are again moved upwardly to their normal position.

The general operation of the device is as follows. The insertion of the coin will cause it to engage the lever 39, or similar 120 levers, that will swing back and bring one rack bar to engage the pinion, that will cause connection of the main operating lever 53 that normally can swing free without operating any of the parts. This lever is 125 now swung forward and down until it engages a stop 92, which will lower the rack bar and at the same time lower the frame that carries the printing wheels. At the same time the arm 62 will by the gears turn 130

the tooth disk and advance the two webs. The previous operation caused the upper web to be cut by the blade 77, and this advance of the webs will bring the upper 5 web beyond the window at 2, and at the end of this stroke of the lever the rack bar and the wheels will make the impression. The lever and other parts will be locked in this position by the described latch, and the auto- 10 graph is now made at the window 2. Thereupon the arm 74 is moved downward which will release the carriage and the spring 34 will retract these parts, causing the arm 62 to further advance the two webs, the upper 15 web passing out at the slot 29, while the other web is wound up on the roll 14 by the described means. At the end of this return stroke the cutter 177 is actuated to sever the upper web only which can be pulled out at 20 the front. It will be understood that this last operation of advancing the two webs will move the portion that receives the impressions beyond the cutter. The final operation will also release the coin that will 25 drop down into a suitable receptacle in the casing.

The printing wheels 29' are shown as turned by a gear 100 that engages a gear 101 carried by a support 102. The clock 30 30 by gears 103, 104 and miter gear 105, rotates shaft 106 through a gear 107, on the end of this shaft. The latter is shown as square and the gear 101 has a square bore so that this gear 100 can slide up and down with 35 the frame, while the shaft 106 does not shift, and is carried by the bracket 108.

One of the uses of the present invention is to permit a passenger in a taxicab or other vehicle, to obtain an accident policy by 40 the mere insertion of a certain coin, and the manipulation of certain parts such as a simple lever and an arm. The coin is inserted and pushed down into the slot, and then a main lever is swung downwardly, 45 which operation will expose the document at a window to receive the autograph of the passenger, or similar data. Then the arm is operated that will connect with the main lever that was swung down, and the mechanism will then advance the document, and 50 cut off the end that is presented at the front opening, to be withdrawn by the passenger. The operation of these parts will cause the date and exact time to be printed on the 55 slip that is discharged, and also indicate the kind of coin by which the operation was produced, and the signature of the passenger will be contained on the document produced. In addition thereto, a duplicate of this doc- 60 ument discharged, will be made on a web or roll of paper, that remains in the casing and cannot be then withdrawn, so that a complete record is retained of all of the documents that are produced. But obvious- 65 ly such a document can be employed for any

purposes whatever, where it is desired to produce a document showing the data, by the use of a coin, or coins of different size.

What I claim is:

1. In a device of the character described, 70 a casing, a printing mechanism in the casing, a control lever, a coin-controlled device arranged to connect the lever with the printing mechanism to advance the latter, a web for printing in the casing, rolls by which 75 the web is carried, means for advancing the web under the printing mechanism when the lever is advanced to receive the impression, and means to further advance the web on the retraction of the lever. 80

2. In a device of the character described, 85 a casing, a printing mechanism in the casing, a control lever, a coin-controlled device arranged to connect the lever with the printing mechanism to advance the latter, a web for printing in the casing, rolls by which 90 the web is carried, means for advancing the web under the printing mechanism when the lever is advanced to receive the impression, means to lock the lever when advanced to hold the web as first advanced, an arm to release the advanced lever, and means to retract the advanced lever and further advance the web. 95

3. In a device of the character described, 100 a casing, a printing mechanism in the casing, a control lever, a coin-controlled device arranged to connect the lever with the printing mechanism to advance the latter, a web for printing in the casing, rolls by which 105 the web is carried, means for advancing the web under the printing mechanism when the lever is advanced to receive the impression, means to lock the lever when advanced to hold the web as first advanced, an arm to release the 110 advanced lever, a cutter on the arm to sever the advanced web, and means to retract the advanced lever and further advance the web. 115

4. In a device of the character described, 120 a casing, a printing mechanism in the casing, a control lever, a coin-controlled device arranged to connect the lever with the printing mechanism to advance the latter, an impression record in the casing for printing, means for advancing the record under the 125 printing mechanism when the lever is advanced to receive the impression, and means to further advance the record on retraction of the lever.

5. In a device of the character described, 130 a casing, a printing mechanism in the casing, a control lever, a coin-controlled device arranged to connect the lever with the printing mechanism to advance the latter, an impression record in the casing for printing, means for advancing the record under the printing mechanism when the lever is advanced to receive the impression, means to lock the lever when advanced to hold the record as first advanced, an arm to release

the advanced lever, and means to retract the advanced lever and further advance the record.

6. In a device of the character described, a casing provided with a window, a time printing mechanism in the casing, a clock arranged to control the time printing mechanism, a control lever, a coin-controlled device arranged to connect the lever with the printing mechanism to advance the latter to print, an impression record in the casing for printing, means to advance the record under the printing mechanism when the lever is advanced to receive the impression of the printing mechanism, a shutter to normally close the casing window and connected with the control lever to be shifted and expose the window, the record as advanced being presented at the window to receive writing thereon.
7. In a device of the character set forth, a casing provided with a window, a time printing mechanism in the casing, a clock arranged to control the time printing mechanism, a control lever, a coin-controlled device arranged to connect the lever with the printing mechanism to advance the latter to print, a web in the casing for printing, means to advance the web under the printing mechanism when the lever is advanced to receive the impression, a shutter to normally close the casing window and connected with the control lever to be shifted to expose the window, the web as advanced being presented at the window to receive writing thereon, means for causing the web as impressed to be protruded from the casing, and means for causing the web as protruded to be severed.
8. In a device of the character set forth, a casing provided with a window, a time printing mechanism in the casing, a clock arranged to control the time printing mechanism, a control lever, a coin-controlled device arranged to connect the lever with the printing mechanism to advance the latter to print, a web in the casing for printing, means to advance the web under the printing mechanism when the lever is advanced to receive the impression, a shutter to normally close the casing window and connected with the control lever to be shifted to expose the window, the web as advanced being presented at the window to receive writing thereon, means for causing the web as impressed to be protruded from the casing, means to lock the lever when advanced to

hold the web as first advanced, an arm to release the advanced lever that is also arranged to sever the web, and means to retract the advanced lever.

9. In a device of the character set forth, a casing, a time printing mechanism in the casing, a clock arranged to control the time printing mechanism, a control lever, a coin-controlled device arranged to connect the lever with the printing mechanism to advance the latter to print, an impression record in the casing for printing, means to advance the record in the casing for printing under the printing mechanism, said coin-controlled device being arranged to be operated by coins of different sizes, and means for making an indication on the record to show which coin was employed for the operation of the device.

10. In a device of the character set forth, a casing, a time printing mechanism in the casing, a clock arranged to control the time printing mechanism, a control lever, a coin-controlled device arranged to connect the lever with the printing mechanism to advance the latter to print, and which device includes a series of plungers each arranged to be put in connection with said lever and printing mechanism but by a different size coin for each plunger, an impression record in the casing for printing, means to advance the record under the printing mechanism when the lever is advanced to receive the impression, and means for printing a character to indicate which coin operated the device.

11. In a device of the character set forth, a casing, a time printing mechanism in the casing, a clock arranged to control the time printing mechanism, a control lever, a coin-controlled device arranged to connect the lever with the printing mechanism to advance the latter to print, and which device includes a series of plungers each arranged to be put in connection with said lever and printing mechanism but by a different size coin for each plunger, an impression record in the casing for printing, means to advance the record under the printing mechanism when the lever is advanced to receive the impression, a printing type on each plunger to indicate the coin used, and which is caused to print in unison with the time printing mechanism.

Signed at New York city, N. Y., on July 8, 1927.

PEARL DOLES BELL.
